(57) **CLAIM**

I claim the ornamental design for a multi-tiered merchandise support assembly, as shown and described.

DESCRIPTION

FIG. 1 is a top, front, and left side perspective view of a multi-tiered merchandise support assembly showing a first embodiment of my new design;

FIG. 2 is a right side elevational view thereof, the left side being a mirror image of the shown;

FIG. 3 is a front elevational view thereof, the rear being a mirror image of that shown;

FIG. 4 is a top plan view thereof;

FIG. 5 is a bottom plan view thereof;

FIG. 6 is a top, front, and left side perspective view of a multi-tiered merchandise support assembly showing a second embodiment of my new design, the only difference from the other embodiments claimed residing in the number of tiers;

FIG. 7 is a top, front, and left side perspective view of a multi-tiered merchandise support assembly showing a third embodiment of my new design, the only difference from the other embodiments claimed residing in the number of tiers; and,

FIG. 8 is a top, front, and left side perspective view of a multi-tiered merchandise support assembly showing a fourth embodiment of my new design, the only difference from the other embodiments claimed residing in the number of tiers. The broken-line disclosure of a support arm in the views is for illustrative purposes only and forms no part of the claimed design.
